UNITED STATES PATENT OFFICE.

GEORGE M. EATON, OF PITTSBURGH, PENNSYLVANIA, ASSIGNOR TO WESTINGHOUSE ELECTRIC & MANUFACTURING COMPANY, A CORPORATION OF PENNSYLVANIA.

TANK STRUCTURE.

Application filed November 1, 1922. Serial No. 598,282.

My invention relates to tanks and it has particular relation to receptacles for oil-immersed electrical apparatus, such as transformers, circuit breakers and the like, and bodies of inert gas above, and in contact with, the oil contained therein.

When a tank adapted to contain an electrical apparatus of the general character designated above is only partially filled with oil, and the space above the oil is occupied by an inert gas, it is very important to reduce the leakage of the gas as much as possible and to minimize the entry of air into the interior of the tank.

When air obtains access to the interior of the tank, it not only carries with it a considerable amount of moisture in suspension which mingles with the oil and diminishes its dielectric properties, but also the oxygen in the air combines with the oil and effects oxidation thereof. Furthermore, in the event that a short circuit or arc develops in the submerged apparatus, hydrogen and methane gases are liberated from the oil that combine with the oxygen in the air within the tank to form a highly explosive gas. If a spark should occur within this gas, an explosion would result, with consequent danger to life and property adjacent thereto.

In order to avoid the objections hereinbefore enumerated, various structures have been designed, but it has been exceedingly difficult to obtain and maintain a hermetic bolted closure or joint between the cover and the body portion of the tank, such as would prevent the leakage of the gas from the tank and the eventual development of an explosive mixture.

One of the objects of my invention is to provide a tank, of the character designated, having a fluid seal which is adapted to isolate the inert gas within the tank and to maintain the same remote from the connection between the cover and the body portion of the tank.

Another object of my invention is to provide a device of the character designated in which the cover portion of the tank carries a continuous depending flange that is adapted to extend downwardly into the body of cooling and insulating oil contained in the lower portion of the tank, thereby avoiding the necessity of providing a separate channel portion for containing a sealing fluid.

A still further object of my invention is to provide a device of the character designated in which a liquid seal is disposed between the cover member and the body portion of the tank, thereby forming a hermetic joint for the tank.

In the accompanying drawings,

Figure 1 is a vertical sectional view through the upper portion of a tank constructed in accordance with my invention, 65 and

Fig. 2 is a vertical sectional view of the upper portion of a tank constructed in accordance with a modification of my invention. 70

Referring to the drawings, and particularly to Fig. 1 thereof, a tank constructed in accordance with my invention is illustrated as comprising a body portion 1, the upper portion of the side walls of which 75 is provided with an outwardly extending flange 2 to which a cover 3 is secured by means of bolts or rivets 4. A gasket 5 may be inserted between the cover 3 and the flange 2. The tank is adapted to contain a 80 body of insulating or arc-quenching oil 6 within which an electrical apparatus, (not shown) may be immersed, and a blanket of inert gas 7 disposed thereabove.

The cover 3 of the tank is provided with 85 a continuous depending flange 8 that is preferably welded thereto and projects downwardly into a continuous channel 9 which extends around the inner surface of the side walls of the tank, adjacent to the 90 upper portion thereof, and contains a body of sealing liquid 10.

By this construction, a fluid seal is interposed between the inert gas within the tank and the connection between the cover and 95 the tank so that the gas confined within the tank may not escape through the connection between the tank and the cover.

In Fig. 2 of the drawings, is illustrated another form of my invention, in which the 100 flange 8 projects downwardly into the main body of oil contained within the tank, thereby providing a liquid seal, without the necessity of constructing a separate channel, as in the construction hereinbefore described. 105

Various modifications and changes may be made in details, and I desire, therefore, that only such limitations shall be imposed as are set forth in the appended claims.

I claim as my invention:

110

1. A tank adapted to contain an insulating liquid and an inert gas and comprising a body portion, a cover rigidly mounted on said casing and non-movable with respect thereto upon change in volume of said insulating liquid, said cover having a depending flange extending into the tank adjacent to its side wall and partly submerged in said liquid. 45
10. 2. A tank adapted to contain an insulating liquid and an inert gas and comprising a body portion, a cover rigidly secured on said casing and non-movable with respect thereto upon change in volume of said insulating liquid, said cover having a continuous depending baffle connected thereto and extending into the tank adjacent to its side wall, the lower edge of the baffle being submerged in said insulating liquid. 50
15. 3. A tank adapted to contain an insulating liquid and a body of inert gas and comprising a body portion having a continuous channel on its inner surface adjacent to the upper portion thereof, said channel containing a body of liquid, and a cover rigidly secured to said tank and provided with a continuous depending flange adapted to extend into said channel and the liquid contained therein to provide a fluid seal disposed between the said body portion and said cover whereby escape of the inert gas contained in said tank is impeded, said cover being non-movable with respect to said casing upon change in volume of said insulating liquid. 55
20. 4. In combination, a casing, a liquid medium and an overlying gaseous medium in said casing, a cover secured to said casing and contacting directly with said gaseous medium, a heat-generating device in said casing and enveloped by said liquid medium, and means for impeding interchange along a path between said casing and cover of the casing ambient atmosphere and said gaseous medium. 60
25. 5. In combination, a casing, a liquid medium and an overlying inert gaseous medium in said casing, a cover secured to said casing and contacting directly with said gaseous medium, a heat-generating device in said casing and enveloped by said liquid medium, and means for impeding interchange along a path between said casing and cover of the casing ambient atmosphere and said gaseous medium. 65
30. 6. In combination, a casing, a liquid medium and an overlying gaseous medium in said casing, a cover secured to said casing and contacting directly with said gaseous medium, a heat-generating device in said casing and enveloped by said liquid medium, and means for impeding interchange along a path between said casing and cover of the casing ambient atmosphere and said gaseous medium, said last-named means comprising a structure forming a liquid seal with said liquid medium. 70
35. 7. In combination, a casing, a liquid medium and an overlying gaseous medium in said casing, a cover secured to said casing and contacting directly with said gaseous medium, a heat-generating device in said casing and enveloped by said liquid medium, and means for impeding interchange along a path between said casing and cover of the casing ambient atmosphere and said gaseous medium, said last-named means comprising a flange projecting from said cover interiorly of said casing and forming a liquid seal with said liquid medium. 75
40. 40. In testimony whereof, I have hereunto subscribed my name this 25th day of October, 1922. 80

GEORGE M. EATON.
